WO WO2007133209 A1 11/2007

Primary Examiner — Freda S Nunn

(74) Attorney, Agent, or Firm — Eric Kelly

CLAIM

The ornamental design for wearable computer case, as shown and described.

DESCRIPTION

FIG. 1 is a perspective view of a wearable computer case according to my new design;

FIG. 2 is a front view thereof;

FIG. 3 back view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged detailed view of the hole pattern as shown in FIG. 2.

Broken lines shown in the drawings represent environment only and form no part of the claimed design.
